UNITED STATES PATENT OFFICE.

ALFRED L. WEISSENTHANNER, OF NEW YORK, N. Y.

METAL CLOSURE FOR BOTTLES, JARS, &c.

SPECIFICATION forming part of Letters Patent No. 783,002, dated February 21, 1905.

Application filed December 17, 1903. Serial No. 135,534.

To all whom it may concern:

Be it known that I, ALFRED L. WEISSENTHANNER, a citizen of the Republic of France, and a resident of the city of New York, in the county and State of New York, have invented certain new and useful Improvements in Metal Closures for Bottles, Jars, &c., of which the following is a specification.

My invention relates to metallic closures for bottles, jars, &c., and more particularly to sheet-metal stoppers having a crown portion and a securing-flange made of a separate piece of metal inclosing a suitable sealing medium and adapted to be bent into locking contact with a shoulder formed near the mouth of the bottle or jar.

As heretofore constructed the ring forming the flange portion of the stopper is slightly flanged at its top to overlie the crown portion of the stopper and is provided with a detachable connection to enable it to be readily released from the bottle or jar to remove the stopper, the detachable connection including a tongue designed to be engaged by the fingers of the user to release the connection. This tongue has been integrally formed with one end of the ring or band forming the flange of the stopper, and as the metal is thin the tongue presents a sharp edge and cannot be readily engaged by the fingers of the opener for releasing the stopper without causing injury or pain, and it is frequently necessary to use some sharp-pointed instrument on the tongue to release the connection so as remove the stopper.

My invention has for an object to provide a construction whereby this defect is removed.

More particularly my invention has for an object to so construct the stopper that the detachable connections of the securing-flange may be readily and easily broken or disengaged by the fingers of the user without causing the slightest pain or injury and without the necessity of resorting to the use of an implement.

These and other objects of my invention will more fully appear from the following description.

My invention consists in the novel parts, im-

provements, and combinations herein shown and described.

The accompanying drawings, which are referred to herein and form a part hereof, illustrate one embodiment of my invention and serve in connection with the description herein to explain the principles thereof.

Of the drawings, Figure 1 is a side elevation of a stopper constructed in accordance with my invention. Fig. 2 is a plan view of the same. Fig. 3 is a side elevation with the detachable connections of the securing-flange released. Fig. 4 is a side elevation, partly in section, illustrating the stopper shown in the previous figures as applied to a bottle; and Figs. 5 and 6 are respectively a top plan and end elevation of a part of the detachable connections, shown on an enlarged scale.

A sheet-metal stopper constructed in accordance with my invention comprises a cover or crown portion and a detachable flange portion consisting of a ring provided with detachable connections and a releasing-tongue having its end made blunt. In accordance with the best embodiment of the invention the end of the releasing-tongue is made blunt by folding the metal inwardly, and the folded end of the tongue is preferably, also, bent transversely to the fold, so that it may be more easily engaged by the fingers of the user.

In accordance with the particular embodiment of the invention illustrated the stopper comprises a crown portion 1, preferably having an integral depending flange 2, adapted to embrace a disk 3, of suitable sealing material, as paper or cork, and a flange portion consisting of a separate ring or band 4, made of sheet metal, having its upper edge flanged inwardly to overlie the upper edge of the crown portion 1, the band being made of such width that its lower edge may be forced into locking relation with an annular shoulder 5, formed on the exterior of the bottle 6 near its mouth. As shown, the flange portion 4 is made of a strip of metal bent into the form of a ring and having its ends detachably secured by interlocking connections consisting of a projection 7, stamped out of the metal of the band near one end and adapted to pass through an opening 8

in a detaching-tongue 9, integrally formed with the other end of the ring. In accordance with my invention the free end of the tongue 9 is made blunt. This may be accomplished 5 in any suitable way. As shown, the end of the tongue 9 is made blunt by making a fold in the metal. This fold preferably and as shown is made by bending the end of the tongue 9 inwardly toward the body of the 10 stopper and backwardly, as at 10, so that the metal thus folded lies in close contact with the body of the tongue. The end of the tongue is thus caused to present a rounded surface, which can be engaged by the fingers of the 15 user without danger of causing pain or injury. In order that the end of the tongue may be more readily engaged by the fingers, the folded end of the tongue is preferably bent or curved slightly transversely to the fold, as clearly 20 shown in Figs. 4, 5, and 6, so that the central part of the tongue is held away from the adjacent surface of the flange portion of the stopper. The user by forcing the end of a 25 finger between the blunt end of the tongue 9 and the flange portion 4 of the stopper may easily force the tongue outwardly, thus bending the projection 7 outwardly and releasing the interlocking connections of the band.

My invention is not limited to the precise 30 construction shown and described, as changes may be made in the details thereof without departing from the main principles of the invention and without sacrificing its chief advantages.

35 Having thus described my invention, what

I claim, and desire to secure by Letters Patent, is—

1. A sheet-metal stopper comprising a crown portion, and a detachable flange portion consisting of a ring provided with detachable 40 connections, and a releasing-tongue adapted to be engaged by the fingers, said tongue having its end made blunt.

2. A sheet-metal stopper comprising a crown portion, and a detachable flange portion 45 consisting of a ring provided with detachable connections, and a releasing-tongue adapted to be engaged by the fingers, said tongue having its end made blunt by a bend in the metal.

3. A sheet-metal stopper comprising a 50 crown portion, and a detachable flange portion consisting of a ring provided with detachable connections, and a releasing-tongue having its end folded inwardly and backwardly with relation to the flange of the stopper. 55

4. A sheet-metal stopper comprising a crown portion, and a detachable flange portion consisting of a ring provided with detachable connections, and a releasing-tongue having its end folded inwardly and backwardly with relation to the flange of the stopper and bent 60 transversely to said fold.

In testimony whereof I have signed my name to this specification in the presence of two subscribing witnesses.

ALFRED L. WEISSENTHANNER.
